UNITED STATES PATENT OFFICE.

SAMUEL C. DERBY, OF ASHLEY, MICHIGAN.

PORABLE ELEVATOR.

SPECIFICATION forming part of Letters Patent No. 373,648, dated November 22, 1887.

Application filed June 20, 1887. Serial No. 241,889. (No model.)

To all whom it may concern:

Be it known that I, SAMUEL C. DERBY, of 5
Ashley, in the county of Gratiot and State of
Michigan, have invented a new and Improved
Portable Elevator, of which the following is a
full, clear, and exact description.

My invention has for its object to provide an
improved portable elevator for use in lieu of
the ordinary ladder, the construction being
10 such that it can be as easily set up or folded as
a ladder, while possessing a much greater car-
rying capacity, and it is simple, strong, and
convenient to operate.

The invention consists in certain novel fea-
15 tures of construction and combinations of parts,
as hereinafter fully described, and particularly
pointed out in the claim.

Reference is to be had to the accompanying
drawings, forming a part of this specification,
20 in which similar letters of reference indicate
corresponding parts in both the figures.

Figure 1 is a side elevation of my improved
portable elevator set up for use. Fig. 2 is a
front elevation of the same.

25 A designates the main or guide frame of the
portable elevator, composed of the parallel side
beams, B B', braced at the top and bottom by
cross-struts C and tie-rods D, and at the mid-
dle of their length by a cross strut, C', arranged
30 to the rear of the forward edges of the beams
B B'.

E designates the rear supporting frame,
hinged to the main frame A by hook-and-eye
35 joints F, so that it can be folded flat thereupon
or detached from the same when not required
for use.

To the forward edges of the side beams, B B',
of the frame A are riveted, or otherwise se-
cured, metal strips G, on which, as ways, slide
40 the parallel side pieces, H H', of the elevator-
car I, also provided with metal strips G', which
ride easily on those on the frame A. Keepers
J are secured to the side pieces, H H', of the
car, slide on the outer faces of the side beams,
45 B B', and are bent inward at right angles to
embrace the same, so as to hold and guide the
car in its movement on the frame A. The side
pieces of the car are extended forwardly at their

lower parts to form brackets K, which rigidly
support a platform, L, on which the user or 50
users stand. The platform L projects rear-
ward between the side beams, B B', of the frame
A, and is adapted to strike the lower cross-
strut, C, which thus acts as a stop to limit the
fall of the car I.

55 Between the upper parts of the side pieces,
H H', of the car is also fixed a shelf or table,
M, on which the various appliances of the user
may be placed, and thus be within convenient
reach of him; and the car is further provided 60
with a back, N, extending between the side
pieces, the lower platform, and the upper shelf,
to more safely hold the user and his tools or
appliances on the car.

Between and in the upper ends of the side 65
pieces, H H', is journaled a horizontal roller,
O, on which is wound a rope, P, attached
thereto, running over a second stationary
roller, Q, journaled in and between the upper
70 parts of the side beams of the frame A, and
thence down to the upper end of the car I, to
which it is attached.

A crank-arm, R, is fixed to the journal of the
movable roller O, projecting through the side
piece H', so that said roller may be turned by 75
the user on the car to adjust himself therewith
to any desired height.

A pawl, S, is pivoted by an eye-joint to one
end of the top shelf, M, and is adapted to en-
gage a ratchet-wheel, T, on one end of the 80
roller O on the car, to hold the same at the de-
sired height.

Having thus described my invention, what
I claim as new, and desire to secure by Letters
Patent, is—

85 In a portable elevator, the combination, with
the guide-frame having parallel side beams
and a car mounted to slide thereon, of a stop
on the lower part of the guide-frame, and a
part on the car projecting between the side 90
beams and adapted to strike said stop, sub-
stantially as shown and described.

SAMUEL C. DERBY.
